UNITED STATES PATENT OFFICE.

REGINALD A. FESSENDEN, OF BROOKLINE, MASSACHUSETTS, ASSIGNOR TO SUBMARINE SIGNAL COMPANY, OF WATERVILLE, MAINE, A CORPORATION OF MAINE.

SIGNALING.

1,182,843.

Specification of Letters Patent.

Patented May 9, 1916.

Application filed September 5, 1913. Serial No. 788,316.

To all whom it may concern:

Be it known that I, REGINALD A. FESSENDEN, of Brookline, in the county of Norfolk and State of Massachusetts, a citizen of the 5 United States, have invented certain new and useful Improvements in Signaling, of which the following is a specification.

My invention relates to the transmission and receipt of power, and particularly to 10 power for signaling, and still more particularly, the directional transmission and receipt of sound signals in water and other media.

It has for its object increased efficiency in 15 such apparatus and methods.

My invention will be understood by reference to the drawings in which—

Figure 1 is a diagram showing the location of the various apparatus on board ship; 20 Fig. 2 is a view showing the various apparatus in diagram together with the electrical connections; Fig. 3 is a longitudinal section of the brush at the change-over station; Fig. 4 is a corresponding section of the 25 switch at the indicator station, and Fig. 5 is a form of receiver which may be used if desired.

Heretofore in the practice of the art, direction has been found wirelessly, by comparing the strength of signals received on antennæ in the form of vertical loops (Fessenden German Patent No. 225,256, Jan. 14, 1907), or by comparing the strength of signals received on vertical antennæ (Fessenden 30 U. S. Patent No. 941,565, Nov. 30, 1909), or by comparing the strength of signals received on horizontal antennæ, at varying angles with reference to the axis of the ship; or by signals transmitted through the air 35 and received by the ear, or on a single receiver, or by signals transmitted through water and received on two microphones, the ship being swung till both microphones give the same intensity of sound.

In the present invention the signals are 40 transmitted and received through the water, thereby avoiding the difficulties due to atmospheric disturbances met with in wireless methods, and the difficulties due to reflection 45 and aerial disturbances when the signals are

transmitted through air. It differs, however, from former submarine methods in the following, among other particulars: 1. Instead of using two or more microphones whose comparative sensitiveness may not remain the same, non-microphonic electric receivers are used which give a definite response to a definite strength of signal. 2. While direction may be located by swinging the ship till the strengths of two signals are 55 the same, direction may also be found by comparing the intensity of two signals. 3. Submarine sending apparatus is preferably used which sends out signals through a limited arc only, preferably about 120 degrees. 4. One sending apparatus and one receiving apparatus is preferably used to send and receive through each 90 degrees of the circumference, and about 15 degrees on each side of the 90 degree arc. 5. In fog or 60 when otherwise desired, signals are sent automatically on each one of the four transmitters, each transmitter sending a different signal.

In Fig. 1, the ship is provided with four 75 sets of apparatus, B, C, D and E, capable of acting both as transmitters and receivers, for example,—the oscillators described in U. S. patent application, Ser. No. 744,793,—the conductors leading from these oscillators 80 running to a central station on the ship at A.

In Fig. 2, is the change-over station; J is the indicator station, both of these being 85 located preferably in the pilot house or station A on board ship. F is a direct current generator and G is an alternating current generator.

The direct current generator F is connected with the field of the oscillators B, C, 90 D and E by the wire f which leads from one set of brushes to the field of each oscillator by means of the branches f¹. Corresponding returns f² lead to the wire f³ in which is a circuit closer f⁴ and which is bridged by one 95 or more resistances f⁵ which as shown comprise two incandescent lamps. The wire f³ continues to the other set of brushes at the generator F. I prefer that a certain amount of current should always flow through the 100

fields of the oscillators to keep them warm, the full field current being thrown in automatically as described below.

The change-over station H comprises an insulated plate (not indicated) on which are mounted segments b , c , d and e . There is also a receiving segment h^s . Between these segments are dead spaces h^s . Mounted on the center of the insulated plate is a rotatable brush or switch comprising two members which cross and are insulated from each other forming four arms h , h^1 , h^2 and h^3 . On the plate are also mounted concentric metallic contacts forming segments of smaller radius than the segments, b , c , d , e and h^s . The outer of these contacts comprises two segments, h^4 and h^5 . Within this is a second series of similar contacts h^6 and h^7 and within that an annular contact h^8 . The segments h^4 and h^5 and the segments h^6 and h^7 are separated by dead spaces h^{10} . The radius of the segments h^4 and h^5 is substantially the length of the arm h^1 of the brush. The radius of the segments h^6 and h^7 is substantially the length of the arm h^2 , and the radius of the inner circle h^8 is substantially the length of the arm h^3 so that each of these arms will act upon its own set of contacts.

The indicator station J comprises an insulated plate (not indicated) upon which is mounted a metallic ring contact J^1 outside of which is a circle comprising segments b^2 , b^3 , c^2 , c^3 , d^2 , d^3 , e^2 and e^3 . Outside of this circle of segments is a series of pins divided into four sets, numbered respectively 20 to 29, 30 to 39, 40 to 49 and 50 to 59. Pins 20 and 29 are connected to wire b^1 by branches b^6 , b^7 and the pins 30 and 39 to wire c^1 by branches c^6 , c^7 , the pins 40 and 49 to wire d^1 by branches d^6 , d^7 and pins 50 and 59 to wire e^1 by branches e^6 , e^7 . Upon the center of this plate is mounted a rotatable switch comprising three separate but mechanically connected arms, j being the longest arm, and reaching the outer circle of the contacts 20, 30, etc., j^1 being in line with said arm but shorter in length to reach the segments b^2 , c^2 , etc., and j^2 being an arm at right angles to the other arms, long enough only to reach the circle J^1 . Normally the arm j^2 is in electrical contact with the arm j but by means of a push button located at j^3 the arm j^2 may be disconnected electrically from the arm j and connected with the arm j^1 .

The alternating current generator G has the usual brushes, one of which is connected by the wire g with the segment h^s in the change-over station H. The other brush is connected by the wire g^1 through a key g^2 with the segment h^s . The contact b at this station is connected by the wire b^1 with the oscillator B. The contact c is connected by the wire c^1 with the oscillator C. The con-

tact d is connected by the wire d^1 with the oscillator D, and the contact e is connected by the wire e^1 with the oscillator E. The circle h^s at the change-over station is connected with all the oscillators by means of the return-wire g^3 . To send a signal by this means, say from the oscillator B, on the port bow of the ship (see Fig. 1), the switch at station H being in the position shown in Fig. 2 (the circuit closer f^4 being first closed to excite the fields in the various oscillators to their maximum and the circuit closer or key g^2 also being closed), the course of the current from the generator G is through the wire g , segment h^s , arms h^1 , h , contact b , wire b^1 and the oscillator B, from thence to the wire g^3 and circle h^s , arms h^3 , h^2 , segment h^s , wire g^1 and its circuit closer to the generator G. A similar circuit can be traced from each of the contacts c , d and e to its oscillator C, D and E upon the movement of the switch to such contact.

The switch h h^1 may be turned about its center automatically and at each contact it may give out a series of predetermined signals, the signals, for instance, of contact c sent by the oscillator C located on the port quarter being, for example, a pair of dots. When contact b is used the oscillator B on the port bow will give out a pair of dashes. When contact d is used the oscillator D on the starboard bow will give say three dots and a dash, and when the contact e is used the oscillator E on the starboard quarter will give a signal consisting of five dots. Mechanism for moving the arms automatically and mechanisms for automatically making and breaking a circuit are well known in the art and hence need not be described. If the switch member be stopped at any one of the segments, b , c , d or e , the key g^2 may be used to send out messages by the Morse or other codes by means of the oscillator in circuit.

The receiving apparatus is out of circuit until in the rotation of the switch at the change-over station the arm h reaches the segment h^s . This brings into circuit a telephone K connected by one wire h with the segment h^s and by another wire k^1 with the segment h^s . Under these circumstances, that is, during the receiving operation, the generator G is cut out from the circuit and, sound waves striking the side of the ship cause the vibration of such of the oscillators as are in reach, which vibration excites a current in whatever circuit is closed. For example, suppose the parts are in the position shown in Fig. 2, where the arm j rests upon the contact 20, the arm j^2 rests as it always will upon the circle J^1 , and the arm j^1 rests on the segment d^2 . Under these conditions the oscillator B will then be in circuit and the current will pass from B through wire b^1 and wire b^6 to contact 20 130

and the arm j and from thence through the arm j^2 to the circle J^1 , thence by the wire h^2 to the segment h^4 , across from h^4 by means of the arms h^1 , h to the segment h^3 , thence by the wire h to the telephone K , by the wire h^1 to the segment h^7 , from h^7 by the cross arm h^2 , h^3 to the circle h^9 and thence by the wire h^3 back to the oscillator B .

Each set of contacts 20 to 29, 30 to 39, etc., is divided into two divisions containing respectively four and six contacts. The contacts of each smaller division are connected by resistances and the contacts of each larger division are connected by resistances as shown. Thus, for example, the oscillator wire b^1 is connected with the contact division 29—24 by the wire b^7 and with the contact division 20—23 by the wire b^6 .

The segments b^2 , b^3 , c^2 , c^3 , d^2 , d^3 and e^2 , e^3 are provided for the purpose of making a comparison between the sounds received by one oscillator and the sounds received by one of the adjacent oscillators without changing the position of the switch j , j^1 , j^2 . For this purpose the contacts 20—23 are connected by the wire b^4 with the segment b^3 which is connected by the wire b^5 with the segment b^2 . The contacts 30—33 are connected by the wire c^4 with the segment c^3 which is connected by the wire c^5 with the segment c^2 , etc.

When the arm j rests on contact 20, as in Fig. 2, the oscillations of the oscillator B on the port bow are heard. Upon the depression of the button j^3 , arm j^2 is disconnected electrically from arm j and is connected with arm j^1 , thus bringing the oscillator D into circuit through segment d^2 , wire d^5 , segment d^3 and wire d^4 , which is connected with contact 40, from which the remainder of the circuit can easily be traced through the receiver K . This enables the officer, by merely depressing the push button, to compare the strength of the vibrations on the two sides of the bow. A similar comparison may be made between the vibrations of any adjacent pair of oscillators. Bearing in mind that, in receiving, the oscillators respond in proportion to the strength of the sound waves, and that the effect of two sets of vibrations of different strengths (*i. e.* coming from transmitters or similar oscillators located at different distances, for example, upon different parts of an approaching ship) may be equalized at the receiving point by the introduction of resistances properly standardized for the purpose, so as to reduce the effect of the stronger vibrations to that of weaker, a method will now be described whereby the course of an approaching ship may be determined as well as the position of the observing ship with relation thereto.

The standardization of the apparatus, that is to say, the adjustment of the resist-

ances for a particular ship may be obtained especially by swinging the ship (as in standardizing compasses) with reference to a source of sound when direction is known. Suppose the source of the sound is on board of another vessel which is sending out the standard signals, each oscillator sending its own signals as referred to above. The switch at station H being on the segment k^8 , the ship is receiving, and the officer by turning the indicator switch handle at J onto 20 listens in on oscillator B , then he listens to oscillator C on the port generator, etc., to determine the general direction from which the sound proceeds. Suppose he hears pairs of dots and also dashes while listening in on B . He knows that the other ship has her port side toward him. He hears the dashes loudest; therefore he knows he is on her port bow. He turns the handle of the switch at J to the left over the contacts 21, 22, etc., listening at each contact until the dashes are reduced in intensity (which may be at the contact 22) so that they equal the intensity of the dots on point 20. If the resistance between 20 and 22 has been standardized so as to correspond to an angle of 20 degrees, the officer then knows that he is 20 degrees off the port bow of the other ship. This gives the course of the other ship is steering.

The officer next proceeds to find the direction of the other ship. He hears the dashes while listening in on contacts 20 and 40, that is, on oscillators B and D . He therefore knows that the other ship is on his bow. He hears the dashes strongest on oscillator D , and knows the ship is on his starboard bow. He turns the switch so that the intensity of the dashes when heard on some contact such as 41 are of the same strength as the dashes heard when the push button is depressed, that is, when listening on oscillator B . From the standardization of the apparatus he knows that this point corresponds to an angle of 30 degrees. He has thus learned therefore that there is a ship 30 degrees on his starboard bow and that this ship is steering in such a course that he is 20 degrees on her port bow. He can also form an approximate estimate of her distance by means of the strength of the signals received.

Instead of using the oscillators as receivers as well as senders, other forms of receiver may be used, provided they are of the non-microphonic kind, *i. e.*, perfect or fixed contacts. Such a receiver is shown in Fig. 5 and consists of a condenser formed of very thin sheets of soft rubber or mica 60 and tin foil or silver 61 deposited on the mica, the whole cemented together into a solid block, preferably under pressure, the cement being a material such as shellac or condensite or bakelite. The condenser block should be

very solid so as to have a high speed of compression elasticity wave propagation through it, preferably of the order of a mile a second. Under these conditions, when a sound wave strikes the side of the ship to which the condenser is affixed, the soft rubber or mica plates 60, are compressed and the silver coatings 61, are brought closer together, thus increasing the capacity of the condenser, and current flows from the battery 62 through the leads 63, 64 and the receiver 65, and the signal is reproduced in the receiver 65. The sensitiveness may be as great as desired by increasing the size of the condenser in area and thickness up to quarter wave length, approximately, and in capacity by diminishing the thickness of the mica or soft rubber plates, or in power by increasing the voltage of the battery 62.

5 The reactances of the condenser and receiver should be equal and opposite in sign so far as possible, *i. e.*, the real parts should be equal and of the same sign, and the imaginary parts should be equal and of opposite sign for the desired signal.

In place of mica or soft rubber other materials may be used provided the velocity of compressional wave propagation is high and preferably of the order of a mile per second. If the velocity is less, the thickness of the condenser must be reduced so that it does not exceed approximately a quarter wave length of the signal. Or if it does, then alternate sections, going away 5 from the side of the ship, should be connected oppositely to each other if in series, or oppositely to the receiver if in parallel so that their effect will not neutralize each other.

6 In place of the tin foil sheets of the condenser shown in Fig. 5, sheets or disks of thin sheet iron or nickel may be used, preferably radially slotted, and the receiving effect obtained by the action of the sound waves in altering the relative position of these iron disks, and thereby increasing or decreasing the reluctance of a magnetic circuit comprising as one element the cylinder made up of said thin iron disks and 5 the separating material, mica, paper, rubber, etc., between them.

It is desirable that the switch f^4 be controlled by a spring which will keep it normally closed and being forked in the customary way to allow the receiver K to be hung from it when the apparatus is not in use so as to open it, thus throwing the current from the dynamo F through the resistances f^5 . When the apparatus is in 5 use the receiver must be removed from the switch to allow the full direct current to pass to the oscillators. As stated above, it is preferable that a partial direct current flow continually through the oscillators to keep them warm.

What I claim as my invention is:—

1. The method of determining the course of a ship which consists in transforming the energy of sets of sound impulses transmitted by a plurality of sounders on said ship 70 into electrical impulses originating in a single source at a receiving station, and equalizing the strength of the electrical impulses originating from one set of sound impulses with those of another set by adding 75 resistances at said receiving station in amounts predetermined according to the relative positions of sources of the sound impulses to said receiving station.

2. The method of determining the course 80 of a ship which consists in transforming the energy of sets of sound impulses transmitted by a plurality of sounders on said ship into electrical impulses originating in a single source at a receiving station, and 85 reducing the strength of the electrical impulses originating from the stronger set of sound impulses by introducing resistances at said receiving station in amounts predetermined according to the relative positions 90 of sources of sound impulses to said receiving station.

3. The method of determining the direction of a ship from a receiving station which consists in transforming sound impulses 95 originating on said ship into electrical impulses at a plurality of sources at said receiving station and equalizing the strength 100 of said electrical impulses by throwing resistances into the path of stronger impulses, said resistances being predetermined according to the relative positions of the source of electrical impulses.

4. In a system of sound signaling, a plurality of apparatuses, adapted to emit 105 sound and to detect emitted sounds, each apparatus being adapted to act over a limited field, and being located with relation to each other whereby said fields will overlap. 110

5. In a system of submarine sound signaling, a plurality of apparatuses, adapted to emit sound and to detect emitted sounds, each apparatus being adapted to act over a limited field, and being located with relation 115 to each other whereby said fields will overlap.

6. In a system of sound signaling, a plurality of apparatuses, adapted to emit sound and to detect emitted sounds, each apparatus being adapted to act over a limited field, and being located with relation to each other whereby said fields will overlap, and means for putting in operation any desired apparatus. 120

7. In a system of submarine sound signaling, a plurality of apparatuses, adapted to emit sound and to detect emitted sounds, each apparatus being adapted to act over a limited field, and being located with rela- 125 130

tion to each other whereby said fields will overlap, and means for putting in operation any desired apparatus.

8. In a system of sound signaling, a plurality of apparatuses, adapted to emit sound and to detect emitted sounds, each apparatus being adapted to act over a limited field, and being located with relation to each other whereby said fields will overlap, means for putting in operation any desired apparatus, and means for changing the function of any desired apparatus from sending to receiving, and from receiving to sending.

13. 9. In a system of submarine sound signaling, a plurality of apparatuses, adapted to emit sound and to detect emitted sounds, each apparatus being adapted to act over a limited field, and being located with relation to each other whereby said fields will overlap, means for putting in operation any desired apparatus, and means for changing the function of any desired apparatus from sending to receiving, and from receiving to sending.

10. In a system of sound signaling, a plurality of apparatuses adapted to emit sound and to detect emitted sounds, each apparatus being adapted to act over a limited field, and being located with relation to each other whereby said fields will overlap, means for putting in operation any desired apparatus, and means for operating said apparatus from a plurality of stations.

35. 11. In a system of submarine sound signaling, a plurality of apparatuses, adapted to emit sound and to detect emitted sounds, each apparatus being adapted to act over a limited field, and being located with relation to each other whereby said fields will overlap, means for putting in operation any desired apparatus, and means for operating said apparatus from a plurality of stations.

12. In a signaling system, a switchboard having a series of sending contacts, a series of oscillators one connected to each of said contacts, said switchboard also having a receiving contact, a receiver connected to said receiving contact, a source of electricity and a switch adapted to connect said source of electricity to said oscillators and complete a circuit through said oscillators and to disconnect said source of electricity from said oscillators and to close a circuit through said oscillators and said receiver.

55. 13. In a signaling system, a switchboard having a series of sending contacts, a sending mechanism connected to each contact, a common source of electricity connected to each sending mechanism and forming a part thereof, a receiving mechanism, a receiving contact connected thereto and located at said switchboard, a receiver connected to said receiving contact, and a switch adapted to connect each sending con-

tact with said source of electricity and also adapted to connect said receiving contact with said receiver and break the contact between said sending mechanism and said source of electricity.

14. A signaling system comprising a plurality of receiving mechanisms, a receiver connected thereto, and a switchboard provided with a plurality of contacts arranged in sets, each receiving mechanism being adapted to be connected with its own set of contacts, resistances connecting certain of the contacts in each set, means for connecting any one of said contacts with said receiver, a sending mechanism, and means for shunting out said switchboard and simultaneously energizing said sending mechanism.

15. A signaling mechanism comprising a plurality of receiving mechanisms, a receiver, and a switch-board provided with a plurality of contacts arranged in sets, each receiving mechanism being adapted to be connected with its own set of contacts, resistances connecting certain of the contacts of each set, a composite switch comprising members adapted to connect each of two sets of contacts in turn with said receiver, whereby the vibrations of two receiving mechanisms may be compared.

16. A signaling system comprising a plurality of receiving mechanisms, a receiver and a switchboard provided with a plurality of contacts arranged in sets, one set for each receiving mechanism, resistances connecting certain of the contacts in each set, and a switch adapted to connect any one of said contacts with said receiver.

17. A signaling system comprising a plurality of combined sending and receiving mechanisms, a source of electricity and a receiver common to all the receiving mechanisms, a switchboard comprising a plurality of contacts, one connected with each sending mechanism and one connected with said receiver and a switch member adapted to engage each of said sending contacts to connect said source of electricity thereto and also adapted to engage said receiving contact whereby it will disconnect said source of electricity from said sending contacts and connect said receiver to said receiving mechanisms.

18. A signaling system comprising a plurality of receiving elements, a switchboard having a plurality of contacts connected to each receiving element, resistances connecting certain of said contacts, a receiver, and a switch adapted to connect any one of said contacts with said receiver, whereby the resistance between said receiver and the receiving element in circuit may be varied.

19. A signaling system comprising a plurality of sending and receiving elements, a receiver, a switchboard having contacts, a

source of electricity, a switch adapted to connect said source of electricity with any one of said sending and receiving elements and also to disconnect said source of electricity therefrom and connect said receiver to any one of said sending and receiving elements, a second switchboard having a plurality of contacts connected to each send-

ing and receiving element, and a switch adapted to connect any one of said contacts 10 with said receiver, and resistances connecting certain of said contacts.
